UNITED STATES PATENT OFFICE.

GEORGE OHDE, JR., AND WILLIAM OHDE, OF MANNING, IOWA.

MOLDING-DISPLAY CABINET.

1,269,208.

Specification of Letters Patent. Patented June 11, 1918.

Application filed March 20, 1917. Serial No. 156,015.

To all whom it may concern:

Be it known that we, GEORGE OHDE, Jr., and WILLIAM OHDE, citizens of the United States, residing at Manning, in the county 5 of Carroll and State of Iowa, have invented certain new and useful Improvements in Molding-Display Cabinets, of which the following is a specification.

Our invention relates to a molding display cabinet, and is especially designed for the use of traveling salesmen for the purpose of enabling them to more readily introduce, display, and sell the goods.

The main object of our invention is to 15 provide a simple, economical, durable and efficient cabinet for displaying moldings, of any suitable size, for the display of said moldings by traveling salesmen, or for use in an office or store for the introduction and 20 disposal of the moldings to the public.

A further object of the invention is to provide a molding display cabinet having a series of hinged leaves or frames within the same, to each of which leaves or frames is 25 transversely and fixedly secured a series of different types or styles of moldings, and adjacent to each sample of molding is fixedly secured a convenient card designating the number of the molding, the price, the 30 number of feet on hand or in stock, and the number of the rack, stall or place where the molding is kept, then by reference to the card the amount desired may be easily obtained.

The foregoing and such other objects as 35 may appear from the ensuing description, are attained by the novel features of construction, arrangement and location of parts hereinafter more fully described, illustrated 40 in the accompanying drawings, and particularly pointed out in the claims appended hereto, it being understood that slight changes in the form, proportion, and minor details of the construction may be resorted 45 to without departing from the spirit or sacrificing any of the advantages of the invention.

Reference now being had to the accompanying drawings which form a part of this 50 specification and in which similar numerals of reference indicate like parts throughout the several views, it will be seen that:

Figure 1, is a perspective view of the improved device embodying our invention.

Fig. 2, is a plan view of the inner face

of the lid or cover of the cabinet removed therefrom, showing the different samples of moldings and the cards secured thereto.

Fig. 3, is a sectional elevation showing in full lines the cabinet in its closed condition, 60 and in dotted lines the position the series of hinged leaves are caused to assume when in open or unfolded position.

Fig. 4, is a perspective view of one of the molding supporting leaves detached from 65 the cabinet.

Fig. 5, is a plan view of one of the cards which is arranged adjacent to each sample of the molding, and

Fig. 6, is a detail sectional view of one of 70 the leaves secured by a spring hinge to the base portion of the cabinet.

In carrying out our invention as illustrated, and which shows a preferred construction, the numeral 1 designates a cabinet which may be of any suitable or desirable size, and of any suitable material, having an open front and a hinged drop-leaf 2, secured to the base portion 3, said drop-leaf forming a closure for the front of the casing, and in which casing a series of molding and card carrying leaves or frames 4, are fixedly secured to a stepped or shelved filling block 5, by the spring hinges 6. To the inner face of each of the said leaves or 75 frames 4 is fixedly attached by screws 7, a series of different types or styles of sample moldings 8, and adjacent to each of the samples is fixedly secured in any suitable manner a card 9 designating the price of 80 each style of molding, the number of the molding, the number of feet of the designated sample of molding carried in stock, and the number of the rack, stall or place in which the indicated sample of molding is 85 kept in stock. Each of the said leaves 4 is provided at its lower end with a lateral extension 10 adapted to rest in contact with the steps or shelves 11, formed on the upper face of the filling block 5, and the upper end portion of each of the leaves is 90 provided with a lateral oppositely disposed projecting extension 12 adapted to rest against the rear face of the leaf in advance of it, when in upright or folded position, and to 95 rest in contact with the upper face of the leaf beneath when in the unfolded or horizontal position shown by dotted lines in Fig. 3, thereby separating each leaf, and avoiding the abrasion or soiling of the series 100

105 110

of samples of moldings carried by each leaf by contact of the leaves with the upper or inner surface of the said moldings.

The outer drop-leaf 2 forming the closure 5 for the cabinet is provided at its lower end portion with an inward extension 13 forming a stop, and at its upper end portion with an outward oppositely disposed extension 14, which is adapted to contact with 10 the support upon which the cabinet rests when the said leaf is caused to assume its unfolded or horizontal position, and the said extension 14 is provided with a suitable eye or staple 15, adapted to engage a suitable 15 hook 16 pivotally secured to the top portion 17 of the cabinet.

Upon the upper face of the top portion of 20 the cabinet is fixedly secured a suitable handle 18 by which the cabinet is conveyed from one place to another.

It will be perceived that the projecting extension 12, secured to the upper portion of each of the hinged leaves 4, is provided with an opening 19 therethrough with a 25 beveled entrance 20 formed around each opening on the lower face of said extension whereby each leaf may be readily engaged by one of the fingers of the operator in manipulating the leaves from their folded 30 position within the cabinet to their down or unfolded position.

It will be seen that the spring hinges assist in returning each leaf to its proper position within the cabinet when the leaves 35 are down or in their unfolded position.

It will be understood that each cabinet may be provided with any suitable or desirable number of hinged leaves required for the purpose of making a complete display of 40 the stock in hand.

The operation of our improved device for the purpose, will be readily obvious from the construction such as illustrated in the accompanying drawings.

Copies of this patent may be obtained for five cents each, by addressing the "Commissioner of Patents, Washington, D. C."

Having thus described our invention what 45 we claim and desire to secure by Letters Patent is:—

1. A molding display cabinet comprising a front drop-leaf forming the closure, an integral stepped filling block secured within 50 the base portion, a series of leaves hinged to said filling block, a lateral extension formed on each leaf at its lower end portion, and an oppositely disposed lateral extension formed on each leaf at its upper 55 end portion, each leaf and the closure adapted to carry a series of sample moldings on the inner face thereof, and means for fixedly securing said series of moldings to each leaf. 60

2. A molding display cabinet comprising a front drop-leaf hinged thereto forming the closure and provided with an inward extension secured to its lower end and an oppositely disposed lateral extension secured 65 to its upper end, said upper extension carrying means adapted to engage a hook pivoted to the top of the cabinet, a shelved filling block secured within the base portion, a series of leaves hinged to said filling block, 70 each leaf having a lateral extension secured to its lower end adapted to contact with one of the shelves of the filling block and an oppositely disposed lateral extension secured to its upper end adapted to contact with the 75 face of the leaf secured in front of it, each of said upper extensions having a beveled portion formed on its lower face with an opening therethrough, and each leaf and the drop-leaf adapted to be provided with a 80 series of sample moldings fixedly secured thereto by a plurality of screws. 85
